US00D810115S

(12) **United States Design Patent** (10) **Patent No.:** **US D810,115 S**
(45) **Date of Patent:** **** Feb. 13, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **Imran Chaudhri**, San Francisco, CA (US); **Christopher Foss**, San Francisco, CA (US); **Chance Graham**, Campbell, CA (US); **Joe Marianek**, San Francisco, CA (US); **Christopher Daryl Soli**, Mountain View, CA (US); **Wan Si Wan**, Sunnyvale, CA (US); **Christopher Wilson**, San Francisco, CA (US); **Chun Kin Minor Wong**, Cupertino, CA (US)

(73) Assignee: **Apple Inc.**, Cupertino, CA (US)

(**) Term: **14 Years**

(21) Appl. No.: **29/473,532**

(22) Filed: **Nov. 22, 2013**

(51) **LOC (11) Cl.** **14-04**

(52) **U.S. Cl.**

USPC **D14/487**

(58) **Field of Classification Search**

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing the claimed design; FIG. 2 is another embodiment thereof; FIG. 3 is another embodiment thereof; and, FIG. 4 is another embodiment thereof.

The broken lines around the figures show a display screen or portion thereof, and form no part of the claimed design.

**1 Claim, 2 Drawing Sheets
(2 of 2 Drawing Sheet(s) Filed in Color)**
